UNITED STATES PATENT OFFICE.

CLARENCE E. LOYD, OF LOS ANGELES, CALIFORNIA.

AUTOMATIC DRILLING-MACHINE.

1,243,616.

Specification of Letters Patent. Patented Oct. 16, 1917.

Application filed August 28, 1916. Serial No. 117,290.

To all whom it may concern:

Be it known that I, CLARENCE E. LOYD, a citizen of the United States, residing at Los Angeles, in the county of Los Angeles and 5 State of California, have invented new and useful Improvements in Automatic Drilling-Machines, of which the following is a specification.

This invention relates to an automatic 10 drilling machine and particularly pertains to a machine adapted to bore holes in sash members for the reception of dowel pins with which said members are held together when assembled.

15 It is an object of this invention to provide a machine which will alternately operate upon the rails and stiles of sash to bore dowel holes in the ends of the rails and at suitable points upon the sides of the stiles, 20 in an automatic manner.

Another object is to provide a simple 25 means for alternately feeding the rails and stiles from separate feed racks to the drills and simultaneously moving the previously drilled members away from the drilling position and out of the machine.

Another object is to provide feed means 30 for withdrawing the lowermost sash member from its rack and positioning it in drilling relation to the drill bits without causing the remaining sash members within the feed racks to forcefully fall the width of the member removed, and thereby eliminating the possibility of the members becoming 35 dented or otherwise damaged by the fall.

Another object is to provide simple means 40 for alternately reciprocating the drill bits on a horizontal plane and at right angles to each other so that the movement of said bits will be in synchronism with the alternate feed of the rails and stiles.

Another object is to provide simple adjustable means whereby the sash members 45 will be positively held against upward movement while being acted upon by the drills and will be readily released therefrom when ejected by the ejecting mechanism.

It is another object to construct adjustable 50 means whereby the position of the drill holes formed in the sash members may be

varied throughout a suitable range of adjustable movement.

Another object is to provide simple adjustable means for regulating the effective 55 boring stroke of the drill bits.

It is another object to provide one of the drilling units with horizontal adjustment so that sash members of various lengths can be accommodated.

It is a further object to provide means for 60 accomplishing the above results in a simple and workmanlike manner and by a machine adapted to operate continuously and automatically from a single source of power.

Other objects will appear hereinafter. 65

The invention is illustrated in the accompanying drawings in which:

Figure 1 is a view in plan illustrating the complete machine as set up for operation and indicating in dotted lines the positions 70 of a sash rail and a stile ready for drilling.

Fig. 2 is a view in front elevation of the complete machine as shown in Fig. 1 and indicates in dotted lines the horizontal position of the sash members while being 75 drilled.

Fig. 3 is a view in section and elevation as seen on the line 3—3 of Fig. 1 and viewed in the direction indicated by the arrows and discloses the relative positions of the vital 80 parts of one unit of the machine.

Fig. 4 is a diagrammatical view in perspective with parts broken away and illustrates the arrangement of the drives of the various elements embodied in one unit of the 85 machine.

Fig. 5 is an enlarged view similar to Fig. 3 of the drawings and with parts broken away to illustrate two steps in the feed operation of one of the machine units, the final 90 step being illustrated in solid lines and the initial step illustrated in dotted lines.

Fig. 6 is a view similar to Fig. 5 with the unessential parts of the machine omitted and illustrates the position of the 95 feed members when a rail is being drilled and further illustrates in dotted lines the intermediate position of the feed members while a stile is being fed to its drilling position.

Fig. 7 is a view of one of the drilling units looking in a direction similar to that of Fig. 5 and with parts broken away to more clearly illustrate the driving mechanism embodied to reciprocate and rotate the drill bits.

Fig. 8 is a view in plan of the drill block operating mechanism provided one of the drilling units and illustrates the essential elements of the mechanism while omitting the bearings and housing therefor.

Fig. 9 is an enlarged view in vertical section as taken through one of the drill blocks and particularly illustrates the drill bit drive and the longitudinal adjustment provided the bit.

Fig. 10 is a view in vertical section as seen on the line 10-10 of Fig. 9 and as viewed in the direction of the arrows and particularly illustrates the arrangement of the driving gears by which the drill bits are rotated.

Briefly considered, the drilling machine comprises a horizontally disposed bed-plate 15 over and at one end of which is fixed a drilling unit —A— and slidably mounted on the bed-plate is a movable drilling unit —B— which is identical in all its details to the unit —A— and is arranged so that complementary parts are adjacent each other for the support and drilling of sash members therebetween. In view of the duplication of the vital parts of the two drilling units, the similar parts will be given like reference numerals wherever they occur throughout the specification.

The bed-plate 15 is formed with parallel ways 16 and 17 which lie horizontally and which are supported upon legs 18 and 19 disposed beneath their opposite ends. The way 17 is graduated along its upper face and enables the operator to set the movable drilling unit —B— for any length of sash. A gear rack 20 is formed along and throughout the inner edge of the way 17 and enables the drilling unit —B— to be horizontally adjusted by means of a wheel 21 mounted upon a shaft 22 which is adapted to rotate a spur pinion 23 in mesh with the rack 20. This shaft is vertically mounted within a suitable bearing 24 upon the main housing 25 of the drilling unit —B— and thereby moves this unit when rotated.

Mounted beneath the bed-plate and rotatably secured within suitable bearings upon the legs 18 and 19 is a horizontally extending drive-shaft 26 which is preferably provided with tight and loose pulleys 27 and 28 adapted to be rotated by engagement with a driving belt 29 which transmits power from a suitable line-shaft. The driving shaft 26 has a relatively small pulley 30 secured upon one of its ends and on the outside of the leg 19. This pulley conveys power to a larger pulley wheel 31 by

means of a belt 32. The belt is frictionally held upon the surfaces of the two pulleys by an idler pulley 33 mounted upon a counterweight lever 34 and acted upon by a counterweight 35. The pulley wheel 31 is secured at the outer end of a worm gear shaft 36 which is mounted at the end adjacent the pulley within a journal box 37 and extends therethrough to a suitable bearing within the fixed drilling unit —A. The driven connections with this shaft will be described hereafter. The opposite end of the drive-shaft 26 is provided with a large pulley wheel 38 which rotates a relatively smaller pulley wheel 39 by means of a belt 40. The pulley wheel 39 is fixed upon one end of a drill bit driving shaft 41 which extends from a suitable bearing 42 upon the housing of the fixed drilling unit —A— through a bearing 43 upon the movable housing and terminating, after passing through a bearing 44, at the end of the bed-plate. The shafts 41 and 36 lie parallel to each other, the shaft 41, however, being positioned above and at the rear of the shaft 36. The shafts 26, 36, and 41, with their various driving and driven pulleys, constitute the transmission of the machine.

As before stated, the drilling units —A— and —B— are formed of duplicate parts and act in an identical manner and for that reason the description following will refer particularly to the unit —B— as it possesses the added function of being horizontally adjusted. This unit is constructed with a housing 25 which is adapted to slidably rest upon the ways 16 and 17 and is secured thereupon by retaining plates 45 and 46. The main portion of the housing is rectangular and contains the driving mechanism required by the stile drilling block 47 and the rail drilling block 48. The drilling blocks 47 and 48 are made in duplicate and are each adapted to move horizontally along parallel guide-ways 49 and 50, these pairs of guide-ways being disposed at right angles to each other within the housing 25.

The drilling block 48 is formed with a rectangular body through which the shaft 41 extends and is adapted to rotate. This shaft is fitted with a driving gear 51 which is provided with extending hub portions adapted to engage the vertical walls of a recess 52 in the drill block. The gear 51 is splined upon the shaft 41 and may be moved throughout the length of this shaft upon the movement of the drill block within which the gear is seated. The drill block 48 is provided with a downwardly extending stud 54 upon the lower end of which is rotatably secured a roller 55. This roller engages a groove 56 formed upon the face of a cylindrical cam 57. The groove 56 is

of a form to cause the drill block 48 to be advanced and retracted throughout a given stroke by the movement of the roller 55 as it passes along the groove. The cam 57 is 5 suitably secured upon a parallel jack-shaft 58 which lies beneath and in vertical alignment with the shaft 41 and is suitably housed within the drilling unit housing. This shaft is adapted to be rotated by a transverse 10 counter-shaft 59 which has a bevel pinion 60 at one end in mesh with a bevel pinion 61 upon the shaft 58. The counter-shaft 59 extends at right angles to the shaft 58 and lies across and above the worm wheel 15 shaft 36 and is driven therefrom by a worm gear 62 which meshes with a worm wheel 63 upon the transverse shaft 59, the gear reduction between the worm gears being sufficient to reduce the speed of travel of the 20 drilling blocks so that proper feed may be had for their drilling bits.

The drilling block 47 is reciprocated by a cylindrical cam 64 secured upon the transverse shaft 59, which cam has a cam groove 25 65 around its periphery. The groove 65 is similar in shape to the groove 56 upon cam 57 but is positioned in relation to the groove 56 so that the blocks will reciprocate toward and from the rail and stile in an alternate 30 manner. The groove 65, as will be understood, engages a roller 55 upon the stud 54 secured to the drill block 47, and thereby reciprocates a spur driving gear 66 within the drilling block. The spur gear 66 is 35 similar to the gear 51 within block 48 and is splined upon a transverse shaft 67 which passes through the drilling block and is driven by bevel gears 68 and 69, the gear 69 being secured to the end of the shaft 67 40 and the gear 68 splined upon the shaft 41. There is no reduction between gears 68 and 69 and in view of the fact that the gears 51 and 66 are of the same diameter the drive provided the drilling bits 70 and 71 upon 45 the drill block 47 and the bits 72 and 73 upon the drill block 48 will be of uniform speed.

The drilling bits are horizontally and rotatably mounted within suitable bearings 50 upon the top of the drilling blocks and are demountably secured within a sleeve 74 which is adapted to be longitudinally adjusted by means of an adjustment screw 75 bearing against the rear end of the sleeve and 55 regulating the stroke of the bit within the sash members. The bit is held in position within the sleeve by a set screw 76 or by other well known means which provides it with lateral adjustment. The sleeves are 60 arranged in pairs and are driven from the gears 51 and 66 by means of pinions 77 and 78 which are staggered in relation to each other to enable the bits to be operated between short centers.

The drill blocks 47 and drills 70 and 71 65 mounted thereupon are adapted to engage and drill the stiles 79 of the sash as they lie parallel upon the two housings of units —A— and —B—. These stiles are normally positioned one upon the other within 70 vertically extending feed racks 80 and 81 which are secured to the housings of the drill units —A— and —B— and are secured a space from the edge of the housing approximately the width of the stile, the space 75 extending along the outer side of the housing forming a drilling platform 82 to which the stiles are delivered prior to being drilled. The stiles are delivered to the drilling platform by means of a feed bar 83 which travels 80 along a horizontal guide-way 84 formed upon the upper face of the drilling unit housing and at right angles to the length of the stile. This bar is not secured to the guide-way but bears upon it and is raised 85 and lowered by a rocker arm 85 to which it is pivotally secured at its outer end by a pivot pin 86. The rocker arm 85 is formed in the shape of a bent lever and bears along 90 its lower face upon a roller 87, the opposite end of the arm being secured to a wrist pin 88 mounted upon a cam 89 which is secured to the shaft 58. The rocker arm 85 is advanced and retracted by the movement of the wrist pin 88, as the shaft 58 revolves, 95 and will, due to its peculiar angular relation to the roller 87, effect a reciprocating and a swinging motion simultaneously. This motion is utilized to advance the feed bar and the stile supporting pad 90 which is 100 secured at the outer end of the feed bar and will, while moving, force the member 90 against the side of a stile to feed it to the drilling platform and thereafter become positioned beneath the stiles within the feed 105 racks and mechanically lower them to the feed floor without violent shock. The stile fed by the feed bar will be placed upon the drilling platform by the end portion of the rocker arm 85 and there left while the 110 rocker arm is retracted and the stile is being drilled.

The movement of the rocker arm not only acts to feed the stiles to a drilling platform but also delivers the rails to their drilling 115 platform. The rails, which are of shorter length than the stiles, are positioned between feed racks 91 and 92 which are secured to the housings of the drilling units —A— and —B— and near the rear of the 120 machine, and these rails are adapted to be drilled by two sets of alined bits 72 and 73. These racks are formed in channel section and are arranged to allow the rails to be fed horizontally therefrom and in a direction 125 opposite to the feed of the stiles. This feed is produced by the return movement of the feed bar 83 which is fitted at the end oppo-

site from the pad with an adjustable pressure screw 93 which bears against the edge of the rail 94 and forces it out toward the rear of the machine and upon a drilling platform 95. The stroke of the rocker arm is sufficient to exactly place the stile and rail in drilling position before the drilling block.

The rail 94, when fed to the drilling platform 95, is forced under a resilient adjustable clamping finger 96 which is curved at its outer end and bears with its arcuate face upon the top of the rail and holds it to the drilling platform. To further secure the rail against movement, a rail locking bar 97 is pivoted to the housing upon a pivotal mounting 98 and extends beneath the rails so that a locking lug 99 formed at the outer end of the bar may be swung upwardly and will engage the inner edge of the rail during the drilling operation, thus preventing the rail from moving backward and against the rail in the feed rack. The swinging of the locking bar is effected by the cam 89 which is formed with a semi-circular cam face which engages a bearing finger 100 extending downwardly from the locking bar and thereagainst. This face is formed with a pause 101 and a swell 102 which extends approximately the length of the cam perimeter and thereby holds the locking bar in its uppermost position one-half the revolution of the shaft 58.

The stile is locked in its drilling position by means of vertically swinging counterweight arms 103 and 104 which are pivoted upon pivot pins 105 and 106 secured within suitable bearings at the rear of the drilling unit housings. These arms are provided with adjustable counterweights 107 which may be slid along the top of the arms to provide proper pressure upon the stile and to act as a counterpoise for the weight of the arm. The stile engaging ends of the arms are formed with side retaining angles 108, presser plates 108', and end engaging angles 109. These angles extend downwardly and secure the stile against outward movement and against end movement while being drilled and the presser plates hold the stile down upon the drilling platform. The oscillating movement of the arms 103 and 104 is afforded by rocker cams 110 which are mounted upon the shaft 58 and are borne against by rollers 111 adjustably secured by means of a threaded mounting 112 to an extension arm 113 secured to the under side of the counterweight arm. The cams 110 represent segmental portions of a disk and are of uniform radius so that when they are in engagement with the rollers 111 the arms will be swung downwardly and around the stile.

When the machine is in operation, the racks 80 and 81 are filled with stiles, one

upon the other, and racks 91 and 92 are filled with rails, positioned in the same manner. The various shafts are then driven by the belt 29 and the drive shaft 26 and this in turn will act to set all of the elements of the machine in synchronous operation. The feed bars 83, of which one is positioned upon each of the drilling unit housings, will be horizontally reciprocated and, we will assume, will first engage one of the stiles 79 and force it outwardly upon the drilling platform 82. As the bars 83 engage the stile the pads 90 thereon are raised to a point upon the level of the top of the stile being fed and will thereafter support the uppermost stile as the lower stile is pushed from beneath it. The rocker arm 85, which is bearing upon the roller 87, will be raised by means of the pin 88 during this forward movement and will thus swing the outer end of the arm down to deliver the stile to the drilling platform without violent shock. The shaft 58 rotates in the direction indicated by the arrow —c— and will begin to retract the feed and rocker bars when the pin 88 has reached the vertical axis of the shaft and further movement will cause the adjustable members 93 upon the rear end of the feed bars 83 to engage one of the rails 94 and force it upon the drilling platform 95 and beneath the pressure finger 96. Simultaneous with the initial movement of the rocker arm 85 to its retracted position, the segmental cam 110 will bear against the roller 111 and act upon the arm 113 to swing the counterweight arms downwardly and over the stile upon the drilling platform. After the rocker arm has been retracted and starts forward the cam 89 will act upon the finger 100 of the lock bar 97 to swing the locking lug 99 up into a locked position against the inner edge of the rail. Thus the rails will be fed and locked and the stiles will be fed and locked in an alternate manner.

The drilling operation of the stiles and rails is effected by the movement of the drill blocks 47 and 48 in an alternate manner and so timed as to drill the stile while the rocker arm is retracting and forcing a rail into drilling position and to drill the rail while the rocker arm is moving forward to feed another stile to its drilling platform. This is accomplished by means of the two sets of cylindrical cams 57 and 64 which alternately reciprocate to produce the correlation above described. It is apparent that the movement of the work on to the drilling platforms will shove the finished pieces out of the machine and on to a suitable rack provided therefor.

It will thus be seen that the drilling machine set forth and described in the drawings and foregoing specification will act in

a continuous automatic manner to alternately feed and drill stiles and rails of window sashes in an accurate manner so that they may be readily assembled and dowled.

I claim:

ranged at right angles to the alined drills, 65
vertical guide racks for the work, a pair of
horizontally reciprocal and parallel feed
bars having engaging members extending
upward and between the bases of said racks,
said feed bars extending in the direction of 70
the parallel drills, means for reciprocating
said bars simultaneously whereby the work
will be alternately discharged from said
racks in opposite directions, one piece of
work being disposed between the alined 75
drills, and the other at right angles to the
parallel drills, in the path of travel of said
drills, and means for reciprocating said
drills whereby holes will be formed in ends
of one of the pieces of work and in the sides 80
of the other pieces of work.

6. The combination of a horizontally extending drill, means for rotating said drill, means for reciprocating said drill intermittently, a feed-bar extending parallel with said drill adapted to engage and advance the work, means for reciprocating said feed-bar intermittently and alternately with the reciprocation of the drill, a pair of rocker arms arranged to rock in a direction at right angles to the direction of reciprocal movement of the drill and feed-bar, means for advancing said arms on the rearward movement of the feed-bar to move same into engagement with the work advanced by the feed-bar whereby the work is held against movement during the reciprocation of the drill, and means for automatically retracting said arms to release the work on the advanced movement of the feed-bar. 10 15 20 25 30 35 40 45 50 55 60 65 70 75 80 85 90 95 100

7. The combination of a horizontally extending drill, means for rotating same, means for reciprocating said drill intermittently, a feed-bar extending parallel with said drill adapted to engage and advance a piece of work, means for intermittently reciprocating said feed-bar alternately with the reciprocation of the drill, a pair of rocker arms arranged to rock at right angles to the drill and feed-bar, means on said rocker arms for engaging the ends of a piece of work, means for normally maintaining said rocker arms in a retracted position, and means operable on the retraction of the feed-bar for advancing the rocker arms and the work engaging means thereon into engagement with the work whereby the latter is held against movement during the reciprocation of the drill. 105 110 115

8. In a machine of the class described, a pair of shafts arranged at right angles to each other, gears feathered on said shafts to shift longitudinally thereof, carriages engaging said gears, a drill spindle mounted on each of said carriages, gears on said spindles meshing with the gears on the shafts, a second pair of shafts extending parallel with the first-named shafts, cams on said

last-named shafts having peripheral grooves, members on said carriages extending into the grooves on said cams, and means for rotating the pairs of shafts simultaneously whereby the carriages will be reciprocated by the cams and the drill spindles rotated.

9. In a machine of the class described, a stationary frame, a pair of housings carried by said frame, a drill in each of said housings arranged in alinement with a drill in the other, a second drill in each housing disposed at right angles to the other drill and arranged parallel to each other, means for delivering pieces of work to the alined 10 drills between the housings, means for delivering pieces of work to the parallel drills alongside of said housings, and means for adjusting the position of the housings in relation to each other to vary the space between the alined drills and the parallel 15 drills.

10. In a machine for drilling dowel holes in sash members, a supporting frame, a pair of housings on said frame, sets of 20 drills operatively mounted within said housings, vertical feed racks secured to the housings, a drilling platform adjacent the feed racks, a feed bar for moving a sash member from the bottom of the feed racks 25 to the drilling platform and lowering the stack, a rocker arm for raising and lowering and reciprocating the feed bar, counterweighted arms pivoted at the rear of the housings and having presser plates to 30 engage on top of the sash member and angles to engage the ends and sides and hold the sash member securely upon the drilling platform, extension arms projecting from the counterweighted arms, and 35 rocker cams engaging the extension arms.

11. In a machine for drilling dowel holes in sash members, a supporting frame, a pair of housings on said frame, drills upon each of said housings, and in alined position to 40 each other, drills upon the housings at right angles to said alined drills, a feed rack adapted to supply work to the alined drills, a feed rack adapted to supply work to the second-named drills, means for locking the 45 work delivered to the alined drills during the drilling operation, and alternately acting means for locking the work delivered to the second-named drills during their drilling operation.

55 12. In a machine for drilling dowel holes in sash members, a supporting frame, a pair of housings on said frame, a set of drills operatively mounted within said housings, vertical feed racks secured to the housings 60 and adapted to receive a stack of sash members, a drilling platform adjacent the feed racks, and a rocker arm and feed bar adapted to deliver one sash member from the bottom of the feed racks to the drilling plat-

form and lower the stack; so that a stack of 65 sash members may be placed in the feed racks and the lower sash member fed to the drilling platform to be operated upon by the drills, and the remaining sash members lowered.

70 13. In a machine for drilling dowel holes in sash members, a supporting frame, a pair of housings on said frame, sets of drills operatively mounted within said housings, vertical feed racks adapted to receive a 75 stack of sash members, a drilling platform adjacent the lower end of the stack space and adjacent the drills, means for feeding the lower sash member from the stack to the platform to be operated upon by the drills, vertically swinging counterweighted arms pivoted at the rear of the housings and having presser plates to press the sash member upon the drilling platform and having angles to engage against the ends of the sash 80 member and against the forward edge, and means for operating the counterweighted arms.

85 14. In a machine for drilling dowel holes in sash members, a set of intermittently 90 moving drills, feed racks disposed adjacent thereto, a feed bar horizontally reciprocated to feed work from the racks to a position in the path of travel of the drills, a rocker arm pivotally connected to the feed 95 bar, means whereby the arm may be reciprocably moved through a vertical plane, and means for causing the rocker arm to raise and lower the outer end of the feed bar as said bar is reciprocated, whereby a 100 piece of work may be fed to the drills and the remaining work lowered to the floor of the feed racks without jar.

15. In a machine for drilling dowel holes in sash members, a set of intermittently 105 feeding drills, a drilling platform in opposition to the drills, vertical feed racks adjacent the platform and adapted to receive a stack of sash members, a horizontal guide-way on a level with the drilling platform, 110 a feed bar sliding upon the guide-way, and a rocker arm for raising and lowering the feed bar and reciprocating the feed bar; so that the feed bar will advance the lower sash member to the drilling platform, then 115 lower the stack, and then retreat to get behind the next sash member.

16. In a machine for drilling dowel holes in sash members, intermittently operating 120 drills, feed racks disposed adjacent thereto and adapted to receive pieces of work superimposed one upon the other, feed means for forcing the lowermost piece of work from the racks and into the path of travel of the drills while the drills are in their inoperative 125 positions, vertically swinging counterweighted arms pivotally mounted and having presser plates to engage on top of

the work and having angles to engage against the ends and forward edge of the work, and means for operating the counterweighted arms.

- 5 17. In a machine for drilling dowel holes in sash members, a set of feed racks adapted to receive superimposed pieces of work, a set of feed racks adjacent thereto adapted to receive other superimposed pieces of work, a feed bar reciprocated between said racks to alternately discharge the lowermost piece of work from each rack, a counterweight arm, means whereby the coun-

terweight arm will be swung into engagement with a piece of work fed from one feed rack, a locking lug adapted to be swung into locking engagement with the piece of work fed from the other feed rack, and means whereby the feed bar may be vertically swung to lower the work within the feed rack to the floor thereof as a piece of work is being fed therefrom.

In testimony whereof I have signed my name to this specification.

CLARENCE E. LOYD.

Copies of this patent may be obtained for five cents each, by addressing the "Commissioner of Patents, Washington, D. C."
